UNITED STATES PATENT OFFICE.

EDWARD W. HARTOUGH, OF DENISON, TEXAS, ASSIGNOR OF TWO-THIRDS TO SVEN P. ALQUIST, OF SEDALIA, TEXAS.

HOT-BOX COOLER.

1,284,327.

Specification of Letters Patent. Patented Nov. 12, 1918.

Application filed July 17, 1916. Serial No. 109,687.

To all whom it may concern:

Be it known that I, EDWARD W. HARTOUGH, a citizen of the United States, residing at Denison, in the county of Grayson and State of Texas, have invented a certain new and useful Improvement in Hot-Box Coolers, of which the following is a full, clear, concise, and exact description, reference being had to the accompanying drawings, forming a part 10 of this specification.

This invention relates to improvements in hot box coolers.

Heretofore, considerable difficulty has been experienced in rapidly cooling hot journal bearings of railway cars while the cars are in motion, due to the fact that the containers of the cooling medium have not been so designed as to permit the direct application of the cooling medium to the hot journals without considerable waste and spilling of the cooling medium.

The object of this invention is to provide an improved cooler more particularly adapted for railway car journal boxes and so designed that the liquid container fits snugly over the journal box and which may be readily placed in position thereon, the discharge of the cooling liquid from the container being controlled by means operable from the exterior of the container after the latter is secured in position on the journal box.

The invention furthermore consists in the improvements in the parts and devices and in the novel combinations of the parts and devices herein shown, described and made the subject matter of claims.

In the drawing forming a part of this specification, Figure 1 is a vertical sectional view showing my improved cooler applied to a journal box. Fig. 2 is a sectional view taken substantially on the line 2-2 of Fig. 1. Fig. 3 is a top plan view of the improved cooler and Fig. 4 is a side elevational view of the cooler, looking toward the inner face 45 of the latter when it is in position.

In said drawing, 10 denotes a journal box of usual type, 11 one end of a journal, 12 the pivoted cover or lid for the journal box, said lid being shown in open position, and 50 13 a portion of the side frame of the car truck. All of the foregoing parts are or may be of usual construction.

The improved hot box cooler is designated generally by the reference A and, as shown, 55 comprises a water tank 14 of relatively large

capacity, an adjustable discharge pipe 15, particularly described hereinafter, and suitable means for attaching the container in position. The container 14 is semi-cylindrical on its outer face as indicated at 16. At each end, the container is provided with a squared section 17 which fit on opposite sides of the journal box, the container being recessed at its center to form an upwardly and inwardly inclined face 18 and an upwardly and outwardly inclined face 19. As clearly indicated in Fig. 1, the inclined face 18 at the center of the container fits against the correspondingly inclined face of the journal box and over the opening therein. The other inclined face 19 is so formed as to provide proper clearance for the open journal box lid, as will be apparent. The discharge pipe or nozzle 15 preferably consists of a substantially Z-shaped section of pipe as clearly indicated in Fig. 2, one end of said pipe 15 being pivotally connected to the container as indicated at 20. The full lines in Fig. 2 show one position of the discharge pipe 15 and the dotted lines indicate the position of said pipe when the latter has been swung through an arc of 180 degrees, it being understood that the axis about which said pipe swings is parallel to and coincides substantially with the axis of the journal. The swiveled discharge pipe 15 is in communication with a pipe 21 preferably lying along the bottom of the container and said pipe 21 has a controlling valve at its inlet end, as indicated conventionally at 22. The valve 22 is controlled and operated by any suitable means such as the rod 23 which extends to the exterior of the container 14 and has a handle 24 thereon by which it may be manipulated. In Fig. 4, the handle 24 is shown in full lines against a stop 25 and indicates the closed position of the valve 22. The dotted lines in said figure indicate the handle 24 against another stop 26 which corresponds to the open position of the intake valve 22. By this means, it will be seen that the control of the water discharged through the pipe 15 is effected from the exterior of the container but at the same time, most of the parts are within the container and thus protected from injury. Water is supplied to the container 14 through the inlet spout 27 having a detachable cap 28.

To maintain the cooler in proper position, the container is preferably provided with a

pair of inwardly and downwardly extended lugs or lips 29 which are adapted to fit over the lower edge of the opening in the journal box, as clearly illustrated in Figs. 1 and 2. 5 A chain 30 is also provided, the same being suitably and permanently attached to the container as indicated at 31 and adapted to be wound around the journal box lid or other suitable adjacent part of the car or 10 truck.

With the construction hereinbefore described, it is apparent that the container is so designed as to hold a relatively large quantity of water or other cooling medium 15 without extending the container outwardly from the car truck to an undesirable degree. Furthermore, the container fits directly over the journal box and substantially closes the opening therein, thus preventing waste or 20 spilling of the water as it is being discharged. By means of the adjustable discharge pipe, it is obvious that the cooling water can be directed to the rising side of the journal, regardless of direction of travel 25 of the car, thus increasing the cooling action since the water will be carried up to the journal bearing and will be retained on the bearing and journal for a longer time than would otherwise be the case if the water 30 were directed to the down-going side of the rotating journal.

Although I have herein shown and described what I now consider the preferred embodiment of the invention, the same is 35 merely illustrative and I contemplate all changes and modifications that come within the scope of claims appended hereto.

I claim:

1. A hot box cooler of the character described comprising, a container recessed on 40 its inner face to thereby fit over the end of a journal box, and means for attaching said container to the journal box or adjacent member.
2. A hot box cooler of the character described comprising, a container recessed on 45 its inner face to thereby fit a journal box or the like, said container being provided with prongs arranged to fit over an adjacent edge 50 of the journal box to thereby support the container, and means for holding said container in position against the journal box.
3. A hot box cooler of the character de-

scribed comprising, a container adapted to fit against a journal box, a discharge pipe 55 leading from said container, and a valve within the container for controlling the discharge of the liquid through said pipe, said valve being operated from the exterior of the container. 60

4. A hot box cooler of the character described comprising, a sheet metal container recessed on its inner face at the center to thereby fit against the end of a journal box, the ends of the container straddling the journal box, said container being provided with a discharge pipe from the inner side thereof at the centrally recessed portion, said discharge pipe being adapted to extend through the opening of a journal 70 box. 65

5. A hot box cooler of the character described comprising, a container, a delivery pipe extending from said container, a valve within the container for controlling the delivery of liquid through said pipe, and a manually operable rod extending from said valve to the exterior of the container whereby said valve may be operated. 75

6. A hot box cooler of the character described comprising, a container, a delivery pipe adjustably and pivotally connected to the container, a pipe extending from said delivery pipe to the interior of the container and having a valve included therein, and 85 manually operable means extending from said valve to the exterior of the container to thereby control the discharge of the liquid through said delivery pipe. 80

7. A hot box cooler of the character described comprising, a container recessed at the center to fit over the end of a journal box, said central portion of the container having an inwardly and upwardly inclined face corresponding to the inclination of the 90 end face of the journal box, said container being provided at the lower edge of said inclined face with an extension arranged to fit over the lower edge of the journal box opening. 95

In witness that I claim the foregoing I have hereunto subscribed my name.

EDWARD W. HARTOUGH.
